United States Patent Office

Des. 204,873
Patented May 24, 1966

204,873

RESTAURANT BUILDING

Wayne Pendleton, Richmond, Calif., assignor to Melvin D. Pendleton, Richmond, Calif.

Filed Nov. 20, 1964, Ser. No. 82,703

Term of patent 14 years

(Cl. D13—1)

FIG. 1 is a front elevational view of my building;
FIG. 2 is a rear elevational view of the building shown in FIG. 1;

FIG. 3 is a side elevational view of the building shown in FIG. 1 and wherein the front elevational portion of the building is at the right of FIG. 3; and

FIG. 4 is the other side elevational view of the build-

I claim:

The ornamental design for a restaurant building, as shown.
